(57) **CLAIM**

The ornamental design for a cactus shaped bottle opener, as shown and described.

DESCRIPTION

FIG. 1 is a top plan view of a cactus shaped bottle opener showing my new design;

FIG. 2 is a bottom plan view thereof and a bottom plan view of a second embodiment of the design, the top plan view being a mirror image thereof.

FIG. 3 is a right side elevation view of both the first and second embodiments of the design;

FIG. 4 is a left side elevation view of both the first and second embodiments of the design;

FIG. 5 is a front elevation view of both the first and second embodiments of the design;

FIG. 6 is a back elevation view of both the first and second embodiments of the design; and,

FIG. 7 is a top perspective view of the first embodiment of the design.
